[57] CLAIM

The ornamental design for a combined packaging and display container, or the like substantially as shown and described.

DESCRIPTION

FIG. 1 is an exploded perspective view of a combined packaging and display container showing the outside of the top portion and the inside of the lower portion of my new design;

FIG. 2 is a perspective view thereof showing the inside of the top portion and the outside of the bottom portion, and looking from the opposite side as seen in FIG. 1;

FIG. 3 is a perspective assembled view thereof;

FIG. 4 is a top plan view thereof;

FIG. 5 is a front side view thereof;

FIG. 6 is a right end view thereof;

FIG. 7 is a left end view thereof;

FIG. 8 is a rear side view thereof; and

FIG. 9 is a bottom plan view thereof.
